UNITED STATES PATENT OFFICE.

WILLIAM H. MILLSPAUGH, OF SANDUSKY, OHIO, ASSIGNOR TO THE SANDUSKY FOUNDRY & MACHINE COMPANY OF SANDUSKY, OHIO, A CORPORATION OF OHIO.

SUCTION-BOX VACUUM-REGULATOR FOR PAPER-MACHINES.

971,298.

Specification of Letters Patent. Patented Sept. 27, 1910.

Application filed October 27, 1905. Serial No. 284,655.

To all whom it may concern:

Be it known that I, WILLIAM H. MILLSPAUGH, a citizen of the United States, residing at Sandusky, in the county of Erie and 5 State of Ohio, have invented certain new and useful Improvements in Suction-Box Vacuum-Regulators for Paper-Machines; and I do hereby declare the following to be a full, clear, and exact description of the invention, such as will enable others skilled 10 in the art to which it appertains to make and use the same.

In paper-making machines of the "Fourdrinier" type, as well as the so-called "cylinder" machines, the paper pulp while forming on the wire or mold, or while on the felt, is passed over a suction-box or vacuum-chamber, for extracting water and moisture from the pulp. It is important to 15 maintain a uniform vacuum in the suction-box, in order to exert at all times an even pull on the wire or felt, and also to accurately govern the amount of the vacuum. The present invention accomplishes these 20 objects by simple and efficient means.

In the accompanying drawings, which form a part of this specification: Figure 1 represents in elevation a suction-box with pump and equalizing apparatus embodying 25 my invention. Fig. 2 is a central vertical section of the equalizing tank and its regulating valve.

A represents in cross-section the wire web or felt which carries the paper pulp over 30 the suction-box B, for extracting the water and moisture from the pulp. A suction-pipe C leads from the suction-box to a pump D. Operation of the pump creates the so-called vacuum in the suction-box, and 35 pumps out the air and water, discharging the same into the open.

Between the suction-box and pump, the pipe C is in communication with a relatively 40 large tank E, placed above the line of said pipe and virtually forming an enlarged part or chamber of the suction-pipe. The function of this tank is to equalize the 45 vacuum and thus maintain an even pull on the wire or felt. To illustrate, in this class 50 of machinery the vacuum for extraction of moisture is usually and preferably attained by means of a positive reciprocating power pump, connected by a pipe line with the suction-box, as illustrated herein. Now the

motion of the pistons being faster at the 55 middle of the stroke than at the ends, ceasing in fact at the ends of the stroke, there results an unequal vacuum or suction, with consequent unequal removal of water, and tendency to lock the wire or felt on the surface of the suction-box, frequently causing 60 damage and also wearing the surface of the suction-box and shortening the life of the wires and felts. Without the tank E, the vacuum gage is seen to fluctuate from practically nothing to the maximum attained at 65 the middle of the stroke. But with this apparatus, the tank E equalizes the suction. It stores vacuum so to speak during the 70 middle of the stroke for the needs of the machine at the ends of the stroke and the vacuum gage shows a uniform and constant vacuum. This insures at all times an even pull on the wire or felt and eliminates the evils of unequal suction entirely, prolonging the life of wires, felts and suction-box 75 covers, and uniformly extracting the moisture from the paper stock. Said equalizing tank E has a regulating valve F, whose office is to govern the amount of the vacuum. 80 It is a simple valve opening inward, and held normally closed or against its seat by a weight G or other pressure, but adapted to open when an excess vacuum occurs within the suction line or tank, such as to cause 85 the outside atmospheric pressure to overcome the weight. For example, if the machine is equipped with a large vacuum pump, and the sheet of paper should suddenly become heavier, an excess vacuum 90 would be instantly created in the suction-box, locking the wire thereof and causing damage. But with this apparatus the vacuum cannot exceed a certain amount, which may be predetermined by the weight, because air is admitted from the outside and 95 breaks the excess vacuum.

The equalizing tank E is preferably a galvanized steel cylinder having closed heads with a nipple at one end for attachment to 100 and communication with the suction-pipe; and the valve F is shown operating in a little chamber attached to and connected to the tank by a short pipe-section.

Paper manufacturers have long suffered 105 from unequal vacuum in suction-boxes, and to obviate the same have used expensive triplex pumps, which are an improvement

over single or duplex pumps, but do not fully equalize the pull. With the present apparatus, however, a perfectly even pull is at all times exerted on the wire, even with the use of single cylinder pumps, resulting in a uniformly dry sheet and a tendency to increase the life of the wires.

Having thus fully described my invention, what I claim as new and desire to secure by Letters Patent of the United States is:

1. The combination, with the suction-box of a paper-machine, and its vacuum-pump connected therewith, of a closed tank or reservoir in constant communication with the suction line or conduit between the suction-box and pump, said tank having an opening and an inwardly-opening regulating valve held to close the same by the pressure in said

tank together with an additional pressure 20 less than that of the atmosphere.

2. A suction-box vacuum-regulator comprising a closed tank having means for connection to the suction-line of a suction-box of a paper-machine and having a valve-controlled opening with a weighted or equivalently-actuated valve held seated against the same and adapted for inwardly-opening under atmospheric pressure when the vacuum in said tank exceeds a predetermined 25 30 amount.

In testimony whereof I affix my signature, in presence of two witnesses.

WILLIAM H. MILLSPAUGH.
